UNITED STATES PATENT OFFICE.

LEONARD M. HALDEN, OF FERGUS FALLS, MINNESOTA.

VALVE-SPRING COMPRESSOR.

Application filed November 15, 1927. Serial No. 233,469.

This invention relates to a valve spring compressor and it consists in the novel features hereinafter described and claimed.

An object of the invention is to provide a compressor of the character stated which is of simple and durable structure and especially adapted to be used for compressing the spring and placing the same in position upon a motor, so that the locking pin may be properly positioned with relation to the spring to hold the same in place while in service.

With this object in view, the compressor comprises a lower jaw member having inwardly and upwardly disposed lugs adapted to receive one end of the spring and an upper jaw member pivotally mounted upon the said lower jaw member. The upper jaw member is provided with upstanding end portions having inturned and downturned extremities adapted to bear against the upper end of the spring. A slide loop is mounted upon the said jaw members and serves to hold the members against spreading movement when the spring is inserted between the jaws. A lever is fulcrumed to the lower jaw member and connected by means of a link with the upper jaw member. When the said lever is swung with relation to the lower jaw member, the upper jaw member is swung upon the lower jaw member so that the spring which is received between the jaw members is compressed. When the spring has been compressed, the loop is slid along the jaw members whereby the spring is held in compressed condition between the jaw members.

In the accompanying drawings:—

Figure 1 is a side elevational view of the valve spring compressor;

Figure 2 is an edge elevational view 40 thereof;

Figure 3 is an enlarged fragmentary sectional view of the compressor showing the same applied;

Figure 4 is an end elevational view of the compressor showing a spring held therein;

Figure 5 is a transverse sectional view of the compressor.

As illustrated in the accompanying drawings, the valve spring compressor comprises a lower jaw member 1. Said member consists of a strip of metal bent between its ends and having spaced side portions. Said jaw member is provided at its working end with upwardly and inwardly disposed lugs 2 upon which one end of a coil spring 3 may rest. An upper jaw member 4 similarly formed,

is pivoted at one end to the jaw member 1 at a point between the ends thereof and the member 4 is provided at its working end with upstanding end portions 5 having inturned and downwardly disposed extremities 6. When the compressor is applied to the spring 3, the extremities 6 are disposed across the upper edge of the spring. A loop member 7 is slidable upon the upper and lower jaw members and may hold the spring 3 in compressed condition. A lever 8 is fulcrumed to the lower jaw member 1 and its working end is connected by means of a link 9 with the intermediate portion of the upper jaw member 4. It is apparent that by swinging the lever 8, the jaw member 4 may be swung to bring the two members into superposed relation and when the said jaw members are so related, the loop 7 may be slid in one direction along the member 1 to hold the members in operative or spring compressed position, or in the opposite direction beyond the end of the member 4, so that the member 4 may swing with relation to the member 1 to inoperative or spring released position. By reason of the fact that the upper jaw member is provided with the upstanding end portions 5, the spring may be inserted in position upon the engine in the event that the engine is provided with the usual web or flange adjacent the cylinder head.

The opposite side portions of the jaw member 1 are pivoted on a pin 10 which passes transversely through the lever 8. The end portions of the pin 10 extend beyond the outer side surfaces of the side portions of the member 1 so that the side portions of the said member may spread in order to receive springs of different diameters between their working ends. A pivot pin 11 passes through the opposite side portions of the jaw member 4 and also passes through the links 9. The end portions of the pin 11 extend beyond the outer surfaces of the side portions of the member 4 so that the said side portions may spread in order that springs of different diameter may be received between their working ends. The lugs 2 carried at the ends of the side portions of the member 1 are upwardly and inwardly disposed as best shown in Figure 4 of the drawing in order that they may engage under and within the lower end of the spring and consequently when they are applied to the spring the side portions of the member 1 can-

not spread upon the pin 10 to such an extent as to permit the lugs 2 to disengage the spring. The extensions 6 upon the upstanding portions 5 of the sides of the member 4 are inwardly and downwardly disposed as best shown in Figure 4 of the drawing and are adapted to engage over the upper convolution of the spring. Thus when the spring is compressed the side portions of the member 4 cannot spread to such an extent as will permit of the extremities 6 disengaging the upper end of the spring.

I claim:

1. A valve spring compressor of the character described, comprising a pair of elongated members, one thereof having pivotal connection with the other for swinging the members into superposed relation, an actuating lever pivotally mounted upon one of said members and having link connection with the other thereof for actuating the members to operative or inoperative position, and means for latching said members in operative position, comprising a substantially U-shaped member overlying one of said first-mentioned members and having the free ends of the legs thereof turned inwardly to engage beneath

the other of the first mentioned members and designed when the members are brought into superposed relation to be slipped forwardly thereon to lock the same in position.

2. A valve spring compressor comprising a pair of jaw members each of elongated substantially U-shaped design, one of the jaws being shorter than the other and having its looped end pivotally mounted beneath the legs of the other jaw to bring the free ends of the jaws into substantial alinement when the same are brought into superposed relation, relatively long pivot pins connecting the legs of the jaw members adjacent the free ends thereof, said jaw legs being freely slideable upon the pins passing therethrough to permit them to spread for engagement about a spring, and a jaw actuating lever mounted upon the pivot pin of one of said jaws and having link connection with the pivot of the other jaw, for drawing the free ends of the jaws together for the compression of a spring engaged therebetween.

In testimony whereof I hereunto affix my signature.

LEONARD M. HALDEN.
